UNITED STATES PATENT OFFICE.

COCIU ENACHE, OF DALLAS, TEXAS.

DOOR CLOSER AND CHECK.

1,398,504.

Specification of Letters Patent. Patented Nov. 29, 1921.

Application filed April 11, 1921. Serial No. 460,303.

To all whom it may concern:

Be it known that I, COCIU ENACHE, citizen of Turkey, (who has signified his intention of becoming a citizen of the United States,) 5 residing at Dallas, in the county of Dallas and State of Texas, have invented certain new and useful Improvements in Door Closers and Checks, of which the following is a specification.

- 10 This invention relates to new and useful improvements in door closers and checks. The object of the invention is to provide a simple and inexpensive device employing a spring retracted plunger and means for retarding the retraction of the plunger whereby the door is gradually closed. And also to arrange the closing means whereby the movement of the door is accelerated as it approaches the closing position and is finally 15 arrested in a closed position.

A construction designed to carry out the invention will be hereinafter described together with other features of the invention.

The invention will be more readily understood from a reading of the following specification and by reference to the accompanying drawings, in which an example of the invention is shown and wherein:

Figure 1 is an elevation of a portion of a 30 door and door frame showing a device constructed in accordance with my invention in position thereon,

Fig. 2 is a vertical sectional view of the device,

Fig. 3 is a transverse sectional view of a portion of the device, and

Fig. 4 is a cross sectional view on the line 4-4 of Fig. 2.

In the drawings the numeral 10 designates 40 an elongated rectangular housing or casing which is provided with ears 11 at its upper and lower ends and flush with its rear side whereby it may be secured to the jamb A of a door frame by means of screws 12. In the lower half of the casing a pair of transverse webs or partitions 13 are arranged transversely and spaced apart so as to provide a guideway therebetween and vertical spaces 14 on each side thereof.

45 Within the guideway is arranged a vertical plunger 15 which carries a cross bar 16 at its upper end normally resting upon the upper edges of the web. Coiled springs 17 have their upper end secured to the ends 55 of the bar 16 and extend down through the spaces 14. The lower ends of the springs

are fastened to eyes 18 at the bottom of the spaces 14.

An eye 19 is provided at the upper end of the plunger and has one end of a cord or 60 other flexible connection 20 attached thereto. The connection 20 passes out through a guide boss 21 at the top of the casing through an eye 22 in the jamb of the frame A immediately above said casing as is shown 65 in Fig. 1. The connection is extended laterally from the eye and is attached to a hook or other connection 23 on the door B. When the door B is open the connection 20 will be pulled through the eye 22 and upwardly 70 through the casing 10, whereby the plunger 15 will be elevated against the tension of the springs 17 to the position shown in dotted lines in Fig. 2. When the door is released the extended springs will pull the 75 cross bar 16 downwardly whereby the connection 20 will be retracted and the door closed.

It will be noted that the plunger 15 tapers upwardly from its lower end at one 80 side, whereby it is given an inclined face 24. The face 24 terminates at its upper end in a notch 25. One of the partitions 13 is provided with a slot 26. A detent 27 extends through the slot and projects into 85 the guideway. The detent is provided with spring arms 28 fastened at their ends on the outside of the slotted partition. Normally the detent projects into the notch 25 as is shown in Fig. 2. This detent has a 90 rounded edge which is presented to the plunger. When the plunger is pulled upwardly the inclined face 24 rides into engagement with the detent 27 and displaces the same outwardly through the slot 26 as 95 is indicated in dotted lines in Fig. 2. The resilient nature of the detent and its arms produces a frictional contact with the face 24 which is increased as the plunger is elevated and decreased as said plunger is lowered, owing to the inclination of the face 24.

100 It will be seen that when the door B is fully open and the springs 17 extended, whereby the plunger 15 is raised to its limit, the detent will be in engagement with the 105 lower end of the face 24. When the door is released the springs 17 will pull the cross bar 16 downwardly, whereby the plunger 15 will be moved downwardly and the connection 20 pulled through the eye 22 to close the 110 door. However, the pressure of the detent 27 on the inclined face will act as the check

and will retard the downward movement of the plunger so that said movement will be gradual and the springs will be restrained in their action. As the plunger descends 5 and the door approaches its closing position the pressure of the detent 27 on the face 24 will decrease and thus the swinging movement of the door will be gradually accelerated until the notch 25 arrives at the detent, 10 when the door will be fully closed and all resistance to the action of the springs and the downward movement of the plunger, will be removed. By this arrangement the door will close properly and during the initial opening movements the tension of the springs 17 will not be retarded because the detent will not ride onto the face 24 until the door has been started on its opening 15 swing.

20 Various changes and modifications may be made without departing from the spirit of the invention.

What I claim, is:

1. In a device of the character described, 25 a supporting structure having a guideway, a plunger mounted in the guideway, a flexible connection attached to the plunger, a coiled spring having one end connected with

the structure and the other end connected with the plunger, and a resilient detent engaging the plunger for retarding its return movement.

2. In a device of the character described, an elongated casing, partitions at the lower end of the casing arranged transversely and spaced to form a guideway therebetween, one of said partitions having a slot, a plunger arranged in the guideway between the partitions and having an inclined face terminating in a notch, a resilient detent extending through the slot of said partitions and normally projecting into the notch of the plunger and disposed in the path of the inclined face thereof, a cross bar in the upper end of the plunger normally resting 40 on the upper ends of the partitions, coiled springs having their upper end attached to the plunger and extending down on each side of the partitions, the lower ends of the springs being attached to the lower portion 45 of the casing, and a flexible connection attached to the upper end of the plunger and extending to the upper end of the casing.

In testimony whereof I affix my signature.

COCIU ENACHE.
